WALL STRUCTURE FOR REFRIGERATOR CARS

James S. Swann, Homewood, Ill., assignor to Standard Railway Equipment Manufacturing Company, Chicago, Ill., a corporation of Delaware

Application August 18, 1955, Serial No. 529,268

2 Claims. (Cl. 105—409)

This invention relates to railway refrigerator cars and has special reference to the structure of the walls of said cars.

Some refrigerator cars are double walled, that is, they are provided with a side plate, side sill, side wall posts extending therebetween and side sheathing secured to said side posts, which constitute the outer wall of the car. Spaced inwardly from this outer wall is an inner wall, which consists of an inner side plate, an inner side sill, spaced inner side posts extending therebetween, and side wall lining secured to said inner posts. Between these inner and outer walls is installed blanket insulation, secured in place in any acceptable manner.

In the so-called top bunker refrigerator cars, the inner wall is constructed to provide vertical flues between the inner posts so that air can circulate by convection currents from the top of the car to the bottom thereof, through said flues.

It is an object of the present invention to provide a novel form of extruded metallic inner side post to reduce the weight of the car and formed in a manner to facilitate the installation of the flue sheets.

It is another object of the invention to form the flue sheets so that they may be sprung into place along their vertical side marginal edges into grooves formed in said posts, along their upper horizontal margin into another groove and fastened along their lower horizontal margin to a car post.

It is a further object of the invention to provide a flue sheet that is easily assembled.

Further objects and advantages of this invention will become evident as the description proceeds and from an examination of the accompanying drawing which illustrates several embodiments of the invention and in which similar numerals refer to similar parts throughout the several views.

In the drawings:

Figure 1 is a partial transverse section of a refrigerator car embodying the invention.

Figure 2 is a section on line 2—2 of Figure 1.

Figure 3 is a broken perspective view of the embodiment shown in Figures 1 and 2.

Figure 4 is a perspective view of a modified form of the invention.

Figure 5 is a horizontal section through the inner wall of the modification shown in Figure 4.

The general parts of the refrigerator car shown are the roof 12, side plate 13, outer wall sheathing 14, side sill 15, spaced wall posts 16, spacer block 17, inner side sill 18, inner side plate 19, inner side post 40, flue sheets 21, lining 22, foraminous floor rack 23, insulated floor 24, and space 25 between the floor rack 23 and floor 24. A hatch 11 is provided through the insulated roof 12 and a ceiling 26 is provided which extends between the inner side plates 19, said hatch 11 extending through said ceiling.

Adjacent the ceiling 26 and inner side wall is a refrigerant container 27 having an opening 28 through the

2

top thereof registering with the hatch 11 through which it may be iced. A drip pan 29 extends from the top of the lining 22 under the container 27 in slightly spaced relation to receive any condensation dropping thereon and to conduct same to a flue 30 formed in the flue sheets 21. Thus, the drip pan 29 and ceiling 26 form an enclosure about the container 27 so that air circulation is from the lading compartment 31 up through the longitudinal center of the car, down between drip pan 29 and ceiling 26 about the container 27 to flues 30 and downwardly therethrough to space 25 and thence upwardly through the foraminous rack 23 to the lading compartment 31 where the cycle is repeated.

A horizontally disposed clip 35 is secured to the inner side plate 19, the lower margin of said clip being offset sufficiently to allow the upper margin 36 of the flue sheets to be inserted between said offset margin and the inner side plate, as clearly shown in Figure 1. The side margins 39—39 of the flue sheet are held by posts 40.

Referring now to Figure 2, the extruded inner side post 40 is a modified H-beam section, the web 41 of which is thickened somewhat as at 42 adjacent one flange 43 which is narrower than the other flange 44. The opposite longitudinal side edges of flange 43 are provided with grooves 47 into which the vertical side margins 39—39 of the flue sheets extend and are held in place by the resilience of the sheets 21. The inner edge 48 of flange 43 is narrower than the outer edge 49 of the same flange.

The flue sheets 21 are formed of light gauge corrosion resisting material, being pressed with a dished or pan-shaped body portion as indicated in Figure 1, to provide the flue area 30. The upper margin 36 and side margins 39—39 of each flue sheet are in the form of lateral flanges occurring substantially in the same plane, whereas as the lower margin 51 projects inwardly and downwardly for attachment as by bolts 54, to the similarly inclined flange 52 of the gutter 53 along the side margin of the car floor.

In installing the flue sheets, the sides of the pan are compressed until the vertical margins 39—39 may enter the grooves 47 in flanges 43 of adjacent posts 40, and then the flue sheet is slid upwardly until the upper horizontal margin 36 extends under the clip 35, when the bolts 54 are applied, and the flue sheet is thus securely held in place.

The car lining 22 is usually of plywood and is secured to the flanges 43 of the spaced inner posts 40. The lower edge of said lining terminates approximately on a horizontal plane with the foraminous rack 23. The vertical edges of the lining meet over an inner post flange 43, and are formed with a shiplap joint as shown in Figure 2. The face of flange 43 is provided with a central row of spaced holes which extend into the thickened portion 42 of web 41 so that self tapping-screws 59 may be applied.

In the alternative form of the invention, shown in Figures 4 and 5, a vertical post 70 is mounted between the inner side plate 19 and inner side sill 18 of a railway car. The vertical post is provided with vertical grooves along opposite sides for holding the side marginal edges of flue sheets 71.

The vertical post has a flange 73, as more clearly shown in Figure 5, provided with grooves 74 in the opposite longitudinal side edges. An outer part 75 and an inner part 76 is formed at each side edge of the flange 73 by the grooves 74. The inner part 76 is of a narrower width than the outer part 75 so as to allow easier insertion of the flue sheets in the grooves from the inside.

70 A web 78 supports flange 73 adjacent an outer flange 80 of the vertical post 70. In this construction the flue

sheets do not have the pan shape construction as the embodiment shown in Figures 1 to 3.

An inner flange 81 is mounted on the web 78 opposite outer flange 80. As shown in the drawing, outer flange 80 extends to one side, while inner flange 81 extends to the other side of web 78. The web 78 is thickened somewhat at 82 adjacent inner flange 81. It will be noted that outer flange 80 is of a larger width than inner flange 81.

The grooves 74 in flange 73 receive the side marginal edges 89 of flue sheets 71. In installing a flue sheet the sides are compressed until the vertical margins 89 enter the grooves 74 in flange 73, and then the flue sheet is slid upwardly until the upper horizontal marginal edge 90 contacts the inner side plate 19.

A block 91 is inserted under the lower marginal edge of the flue sheet resting on inner side sill 18. A drain board 92 may be inserted above block 91 and under the marginal edge 94 of the flue sheets 71 and extended over the inclined flange 95 of a gutter 93.

The car lining 22 of plywood is secured to inner flanges 81 of the spaced inner posts 70. The vertical edges of the lining meet over the inner post 70 and are formed with a shiplap joint, as shown in Figure 5. The face of flange 81 is provided with a row of spaced holes which extend into the thickened portion 82 of web 78 so that self-tapping screws 59 may be applied.

In the drawing and specification, there have been set forth several embodiments of the invention, and although specific terms are employed, they are used in a generic and descriptive sense only and not for purposes of limitation. Changes in form and in the proportion of parts, as well as the substitution of equivalents are contemplated, as circumstances may suggest or render expedient, without departing from the spirit or scope of this invention as further defined in the following claims.

Also it will be noted that being extruded, the inner post may be formed to provide the required strength in accordance with the kind of metal used.

I claim:

1. In a refrigerator car wall having an inner side sill and inner side plate, vertical posts extending between said

sill and plate and connected at their ends thereto, said posts having a web supporting an inner flange normal to and extending equally on opposite sides of said web, said web being thickened adjacent said inner flange, a groove along each vertical longitudinal edge of said inner flange, flue sheets between said vertical posts, each flue sheet having a generally pan shape body portion with side marginal edges compressed so as to enter said grooves of said inner flange and held therein by their inherent resiliency, and lining secured to the inner face of said flanges by fastening means extending through said lining and into the thickened portion of said web.

2. In a refrigerator car wall having an inner side sill and inner side plate, spaced vertical posts extending between said sill and plate having a web supporting an inner flange normal to and extending equally on opposite sides of said web, a groove along each vertical longitudinal edge of said inner flange, said web being thickened adjacent said flange, flue sheets extending between said vertical posts, said flue sheets having a body portion with side and top marginal edges in the same plane, said side marginal edges being compressible so as to enter said grooves of said inner flange and be held therein by their inherent resiliency, a clip member secured to said inner side plate for holding said top marginal edge, and lining secured to the inner face of said flange by fastening means extending through said lining and into the thickened portion of said web.
